UNITED STATES PATENT OFFICE.

HONORÉ MARTINEAU, OF HOLYOKE, MASSACHUSETTS.

SAFETY DEVICE FOR ELEVATORS.

No. 922,607.

Specification of Letters Patent.

Patented May 25, 1909.

Application filed April 28, 1908. Serial No. 429,646.

To all whom it may concern:

Be it known that I, HONORÉ MARTINEAU, a subject of the King of England, residing at Holyoke, in the county of Hampden and 5 State of Massachusetts, have invented new and useful Improvements in Safety Devices for Elevators, of which the following is a specification.

This invention relates to improvements in 10 safety devices for elevators and more particularly for freight elevators.

The object of the invention is to provide an attachment or mechanism for freight elevators, whereby the upward movement of the 15 elevator will be instantly stopped in case any object carried thereon projects beyond the platform of the car and would strike the edge of the opening in the floor through which the car passes and constituting a part of the ele- 20 vator-shaft.

Broadly, the invention consists in associating with the shipper-rod of the elevator, mechanism by which the car during its upward movement will be instantly locked to 25 the shipper-rod, whereby the mechanism which raises and lowers the car will be rendered inoperative.

Referring to the drawings forming a part 30 of this application,—Figure 1 is a perspective view of a freight elevator showing the same about to pass through an opening in the floor of a building and with the attachments operatively arranged with relation to the car for operating the shipper-rod. Fig. 2 is a 35 transverse sectional view through the shipper-rod and rack-bar on the line 2—2 of Fig. 1 looking in the direction of the arrow and before the car is locked to the shipper-rod. Fig. 3 is a view similar to Fig. 2 after the 40 locking engagement of the car and the shipper-rod is effected.

Referring to the drawings in detail,—*a* designates a portion of the flooring of the building provided with the usual elevator-shaft or 45 opening *b*. The car shown in the drawing is that of a freight elevator and is designated by *c*.

Secured by bolts or lag-screws to the underside of the flooring *a* are depending brackets *d* and *d'*, and pivoted to the bracket *d* is an elbow-lever *e* having the arms *f* and *g*, and pivoted to the bracket *d'* is an arm *h*, the arms *g* and *h* being connected together by means of a bar *i*.

55 The arm *f* has attached to it a cord or chain *j* that passes through a ring-shaped

opening in the bracket *k*, its other end being attached to a finger *m* that is rotatably mounted on the shipper-rod *n* by means of the loose collar *o*, that is connected to a 60 coiled spring *p*, the other end of the spring being attached to the collar *r* that is fixed to the shipper-rod *n* by means of the set screw *s*. The spring *p* acts normally to move the finger *m* away from the teeth of the rack-bar 65 *t* that is carried by the car *c*. Located above the collar *o* is another collar *u* secured to the rod *n* by means of a set-nut *v*. This collar is provided with a stop *w* against which a pin *x* strikes for limiting the outward movement 70 of the finger *m*.

The shipper-rod *n* extends the entire height of the building and is loosely mounted in the different floors so that the operator of the car can raise and lower the same when 75 starting and stopping the car by means of the usual handle *P*. The opposite side of the elevator opening is provided with brackets similar to *d* and *d'* only one of which is shown, and a cord or chain *q* that extends 80 through the bracket *k* is also secured to the finger *m*.

The shipper-rod *n* is normally held so that the finger *m* is out of engagement with the teeth *u* of the bar *t*, that is to say in the position shown in Fig. 2.

2 designates an object or piece of freight on the platform of the elevator that is shown projecting beyond the vertical edge *y* of the car, and in engagement with the under side 90 of the horizontal bar *i*. The continued upward movement of the car will bring the block or object 2 into contact with the bar *i* thus elevating the arms *g* and *h* and causing the arm *f* to draw on the cord or chain *j* in 95 the direction of the arrow. This action will rotate the finger *m* against the tension of the spring *p*, by means of the chain *j*, into locking engagement with the teeth of the bar *t* which will lock the car to the shipper-rod, thus elevating the same and causing the actuation of the usual belt-shipping and driving mechanism (not shown) so as to stop 100 the car before any damage is done to the flooring or elevator on account of the object 105 2 projecting beyond the edge *y* of the platform.

After the stopping of the car the operator can of course move the shipper-rod so as to impart a reverse or downward movement 110 to the same, thus permitting the object 2 to be removed as readily understood

What I claim, is:—

1. In combination with an elevator-car, means for starting and stopping said car, said means comprising the usual shipper rod, a locking finger carried by the shipper-rod, a rack carried by said car, and automatically operated means for moving the locking finger into engagement with the rack.
2. The combination with a shipper-rod, 10 an elevator-car, a finger carried by said rod,

a rack carried by said elevator-car, means for normally retaining the finger away from the rack, and automatic means for locking the finger and rack together during the movement of said car, as described.

HONORÉ MARTINEAU.
